CLAIM

The ornamental design for a scale, as shown and described.

DESCRIPTION

FIG. 1 is a top and right front isometric view of a scale showing my new design;

FIG. 2 is a top plan view thereof;

FIG. 3 is a right side elevational view thereof as taken from arrow III of FIG. 2;

FIG. 4 is a left side elevational view thereof as taken from arrow IV of FIG. 2;

FIG. 5 is a bottom plan view thereof;

FIG. 6 is a rear elevational view thereof as taken from arrow VI of FIG. 2;

FIG. 7 is a front elevational view thereof as taken from arrow VII of FIG. 2.
